Primary Examiner — Marissa J Cash(74) *Attorney, Agent, or Firm* — Sterne, Kessler, Goldstein & Fox P.L.L.C.**CLAIM**

The ornamental design for an aerial vehicle, as shown and described.

DESCRIPTION

This application is related to U.S. Design patent application Ser. No. 29/654,658, titled “Battery”; U.S. Design patent application Ser. No. 29/654,663, titled “Camera”; U.S. Design patent application Ser. No. 29/654,665, titled “Camera with Gimbal”.

FIG. 1 is a top rear perspective view of an aerial vehicle showing the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the aerial vehicle that form no part of the claimed design.

1 Claim, 6 Drawing Sheets(56)
